UNITED STATES PATENT OFFICE.

WILLIAM HOCHHAUSEN, OF NEW YORK, N. Y.

APPARATUS FOR REGULATING AND DISTRIBUTING CURRENTS FROM DYNAMO-ELECTRIC MACHINES.

SPECIFICATION forming part of Letters Patent No. 295,552, dated March 25, 1884.

Application filed May 4, 1883. (No model.)

To all whom it may concern:

Be it known that I, WM. HOCHHAUSEN, a citizen of the United States, and a resident of New York, in the county of New York and State of New York, have invented certain new and useful Improvements in Regulating and Distributing Currents of Dynamo-Electric Machines, of which the following is a specification.

10 My invention relates to the method of regulating and distributing the currents from dynamo-electric machines. Its object is, in the first place, to provide a means for automatically changing the electro-motive force of the 15 current upon the exterior or working circuit to suit the changed resistance consequent upon the cutting out or in of an electric lamp, motor, or other translating device.

A further object of the invention is to provide 20 an arrangement of circuits and regulating devices whereby several independent circuits may be worked from the same generator, and the supply of current to such circuits may be regulated in accordance with the changes 25 in any circuit, without affecting or being affected from other circuits.

My invention consists in certain novel combinations, that will be specified in the claims following the description of the figures of 30 drawings.

Figure 1 is a perspective view, showing a series of adjustable commutators, and illustrating the construction of apparatus which I have devised for supporting and adjusting a 35 large number of pairs or sets of commutator-brushes on the same commutator-cylinder. Fig. 2 shows in side view one form of device that may be used for shifting the commutator-brushes, and illustrates, diagrammatically, the 40 connection of said brushes with a multiple-are working-circuit, and with the controlling-magnet, by which the adjustment of the brushes to suit changes in the working-circuits is effected. Fig. 3 is a diagram of 45 circuits and connections, showing the application of my invention to several working-circuits, each of which supplies current to electric lamps or other translating devices arranged in multiple-are connections.

50 Referring to Fig. 1, A A indicate the field-magnets of a dynamo-electric machine of any

preferred construction, and B B the field-of-force pole-pieces, between which the armature rotates. The form of machine, however, with which I prefer to use the arrangements hereinafter described is that in which a ring-armature, wound after the style devised by Paciotti, and afterward by Gramme, is employed. 55

C indicates the commutator-cylinder, to which the armature-coils are connected in any usual way, said cylinder being here shown as elongated somewhat beyond the extent employed in practice, for the purpose of showing more clearly the parts.

E² indicates the usual adjustable support 65 for the commutator-brushes of the machine, the brushes supported thereby being connected to the field-magnets so as to energize the same after the manner illustrated in Fig. 3, and to be hereinafter more fully described. 70

E E, &c., are supports for additional or auxiliary pairs or sets of commutator-brushes, each pair or set being connected with a separate working-circuit of any kind. These supports consist of rings or annuli surrounding 75 the commutator-cylinder, and supported by a series of grooved friction-rollers, F F² F³. The upper rollers, F, are supported on a spindle, F⁶, mounted in brackets f³, one of which is attached to the field-of-force pole B, while the other is mounted on the journal-box d, for the armature-shaft. The rollers F² are supported on a similar rod, F³, mounted in brackets f f, one carried by the lower pole-piece, B, and the other by an arm, F⁴, of a standard supported on the base of the machine or otherwise. The rollers F³ are supported in similar manner from another arm. E³ indicates an additional support, mounted on the journal-box 85 for the shaft, by means of a ring or collar, e, 90 from which extend arms g, united by a segmental rack, h, with which engages a pinion, i, on the shaft of an electric motor, I. This motor serves to adjust the brushes forward or back, to suit any changes in the resistance of 95 the working-circuit supplied from the commutator-brushes G G², said motor being controlled in the manner which is hereinafter described. Each of the supporting-rings E carries a rack, k, by means of which the ring may 100 be adjusted in a similar manner to E³. I have herein shown the adjustment as effected by

means of an electromotor, J, and a vertical rack, K, said rack engaging with the segmental rack k and with a pinion, j, on the motor-shaft. The remaining rings or brush-supports E are adjusted by similar means. Brush-support E² is provided also with a segmental rack, h², formed on or attached to its edge, with which engages a pinion, I², on the armature-shaft of an electric motor of any desired construction—such, for instance, as that indicated at I—which comprises an annular armature, constructed and wound in the usual way adopted with machines of the Gramme or Pacinotti type, and revolving between the stationary pole-pieces A⁴ A⁵ of an electro or permanent magnet. The pole-pieces for the motor, which serves to shift the support E², are indicated at I², and are magnetized by attachment to the pole-pieces of the dynamo-machine.

I have herein shown and shall describe the adjustment of the commutator-brush supports as effected by means of electric motors automatically controlled; but I do not limit myself to such a means of adjustment, but may employ any device which will respond to or act in accordance with the changes of current on any circuit connected to a pair or set of brushes, so as to shift the brush support and the brushes, and vary the current taken off by such brushes, so as to keep the current on the working-circuit constant.

In Fig. 3 the brushes H H², which are carried by the support E², are shown as connected with the field-magnets A A, so that the current taken by said brushes will energize the field-magnet. The brushes for the additional or auxiliary supports E supply, each pair, a separate working-circuit, 5 5, to which are connected, in the present instance, electric lamps S or other working resistances. In one of the multiple-arc connections for each circuit 5 5 is a governing electro-magnet, N, by means of which the operation of the electric motor which serves to shift a brush-support, E, is governed. The arrangement of circuits and devices which may be employed for this purpose is indicated in Fig. 2. The actuating motor I is shown with its stationary pole-pieces removed for the sake of simplicity. This motor is energized by a current taken from the main conductors 5 5, through a multiple-arc circuit, 7 7, the current of which is made to pass through the motor in one direction or the other by a device and arrangement of circuits, which is described and claimed in another application for patent filed by me, and is substantially as follows:

N² indicates a circuit-closing armature-lever governed by electro-magnet N, and connected by wire 7 with one of the main conductors, 5. N³ is a double contact-lever having two contact-points, n n², insulated from one another, and which are adapted to bear singly or together on contact-lever N², and are connected, respectively, through branch wires 9 9, with resistances R² R, and thence with the other cir-

cuit-wire, 5. From points x x in the two branches connections are taken to the commutator-brushes L L² of the motor, one of said connections including an electro-magnet, I⁶, controlling an automatic stop or brake for the motor, which stop or brake is mounted or supported by the armature-lever of the electro-magnet I⁶, and is so arranged as to engage with the serrated brake-wheel i when the electro-magnet I⁶ loses its power. This arrangement of brake is not herein claimed, as it forms the subject of claims in another application for patent filed by me.

It being premised that the field changes in magnetism of the machine are connected so as to keep the magnetism constant, by the arrangement to be presently described, the operation of the devices, as thus far described, would be as follows: When the whole number of lamps S S or other translating devices are in use, and the total working resistance is therefore normal, the magnet N will hold the armature N² up with sufficient force to preserve a contact with both points n n², and no current will flow through the motor, the resistances R R² being equal, and the bridge-wire, which includes the magnet I⁶, and the motor being connected to the two branch-wires 9 9 at points of equal potential. The motor, therefore, will remain at rest, and the brushes H H² will retain the position suited to the supplying of a current adapted to the total number of lamps or other translating devices, and the total amount of resistance in the working-circuit. If, now, a number of lamps be removed, so as to increase the amount of current flowing in any lamp, and to, in consequence, require a change in the current supplied, the magnet N will increase in power and will draw the contact-lever N² over, thus causing the contact-points n² n to rock on the same, and will cause a break of contact at n, contact at n² being preserved. The current will then flow from n², through 9, to point x, where it will divide, one portion passing through resistance R and the other through magnet I⁶, the electric motor, and resistance R². The portion diverted into the latter circuit will depend on the amount of resistance R, which is made suitable for the purpose. The motor will be thus caused to rotate, the brake being simultaneously withdrawn, and the brush-support E will begin to move forward, so as to cause a diminution in the electro-motive force of current supplied to the circuit 5 5, and a consequent diminution in the current flow. This forward movement will continue until the current in each multiple-arc branch and the strength of magnet N are restored to normal, when armature-lever N² will recede to its normal position, and both contacts n n² will be closed, so that the motor will cease to revolve and the brushes will come to a stop. At the same instant that current ceases to flow through the motor the magnet I⁶ will lose its power and the brake will therefore be instantly applied, so as to

bring the motor immediately to rest. If, now, lamps or other translating devices be thrown into circuit, thus requiring more current to be supplied to the circuit 55, the normal magnetism of N^1 will decrease so that the retractor of N^3 will move the double contact-lever and cause the same to rock on armature-lever N^2 , so as to break contact at n^2 , while preserving it at n . The current will thus be caused to circulate in the electric motor in an opposite direction, and the brushes H H^2 will be shifted backward until the current taken off by them attains its normal and the magnetism of N becomes sufficient to restore the parts to their normal condition, and thus cause the motor to come to rest. Each working-circuit and its independent pair of brushes is supplied with similar apparatus, so that the currents for them, although supplied from the same machine, may be adjusted independently of one another to suit any changes in any working resistance.

I do not limit myself to the devices herein described for shifting the brush-holder automatically in accordance with the changes of the working resistance, since the same result might be accomplished by other means. The brush-holder E^2 for the brushes which supply current to energize the field-magnets is adjusted in a similar manner, by devices controlled by an electro-magnet in the field-magnet circuit, or by the movements of an armature placed within the influence of the field-magnet. I have herein shown the brush-holder E^2 as worked by an electromotor, the outline of whose armature is indicated at I^3 , which motor is geared to the brush-support E^2 in substantially the manner indicated in Fig. 1. The motor is supported by the field-magnet or by other means in any suitable manner. It is placed by preference in the direct circuit, including the field-magnets, as indicated in Fig. 3, and the movement of said motor is controlled by an armature, B^6 , supported by the field magnet frame within the attractive influence of the head of the magnet and arranged to act on a double contact-lever, N^3 , in the same manner that armature-lever N^2 of Fig. 2 operates. When the field-magnetism is of the normal or proper strength the armature B^6 is drawn up with sufficient force to keep both of the branch circuits, including the resistances R^2 R , closed, so that the motor will remain at rest, and the brushes H H^2 stationary. If, for any reason—as by a change of resistance in one of the exterior working-circuits—the field-magnetism should tend to increase, the apparatus at O will correct such tendency, because the armature B^6 would be drawn up with an increased attraction, and would therefore cause a rotation of the motor in such a direction as to shift the brush-holder forward to a position where the current taken off by the brushes would be less. Such forward adjustment would continue until the field-magnetism resumed its normal strength,

when the adjustment would cease, for reasons already explained, and the brushes would remain stationary until there were a further change, either by way of increase or decrease in the strength of the field-magnets, when a further adjustment would occur to restore the magnetism to its normal, and to hence keep the magnetism of the field constant, and the strength of the current which the armature would normally supply to the exterior or working circuits the same. The field-magnetism, with the arrangement of the circuits shown in Fig. 3, is virtually supplied by a derived circuit from the working-circuits. Its constancy may be maintained by any other desired arrangement of mechanism, or of magnets, for automatically controlling such mechanism, the gist of my invention, so far as this feature is concerned, consisting in keeping the field-magnetism constant, while the various working-circuits are supplied from the same armature by auxiliary sets of brushes, and the currents upon such circuits are independently and automatically controlled.

The commutator-brushes supported by E^3 are adjusted to supply current to any desired circuit in the same manner as those already described. The automatic brake might be applied to advantage with the motor which shifts the brushes connected to the field-magnet.

It is within my invention to shift any one or more of the brush-holders E by hand, instead of automatically; and my invention possesses special advantages in this respect that adapt dynamo-machines for use in lighting theaters or other places where it may be desired to supply independent circuits or lights from the same armature, and to allow the lights in any one or more circuits, to be increased or diminished at pleasure, while the lights of others remain constant, or are also increased or diminished. For instance, one of the circuits supplied from a set of brushes may convey the currents to the foot-lights for the stage of the theater, and the brush-support may be shifted by hand to turn the lights down or up when desired. The other circuits may, meanwhile, supply the lighting-currents in the usual way to lights that are intended to be constant; or other circuits in the house may be controlled by hand as well as the circuits supplying the foot-lights; or the relays which control the motors may be arranged at any convenient place in a theater—for instance, at the prompter's desk—and the retractile spring of the relay may be adjusted by any desired means, so as to vary the amount of light, as desired. As shown in Fig. 2, the retractile spring is adjusted by means of a pointer, P^5 , moving on the face of a dial, which may be graduated for candle-power, so that the set of lamps can be made to give any degree of illumination, from zero up to the maximum the lamps will stand, by simply moving the pointer according to the indications of the dial.

I do not limit myself to the manner of sup-

porting the auxiliary sets of brushes, as other means may be used without departing from the invention.

My invention may be applied to other working-circuits besides so-called "multiple-arc circuits," and the controlling electro-magnet N may be arranged in other positions or connections without departing from the invention.

10. What I claim as my invention is—

1. The combination, with a dynamo-electric machine whose field-magnetism is sustained by a derived-circuit current from the armature, and is automatically corrected, by any suitable means, to suit any change in the external or working circuit, so as to remain constant, of an automatic regulator for adjusting the current in such working-circuit to any changed resistance therein.

2. The combination, in a dynamo-electric machine having a commutator provided with two sets of brushes, of a field-magnet supplied with current from one set of brushes, means for automatically adjusting said brushes so as to correct any changes in the magnetic force induced by the current from said brushes, and keep the magnetism constant, an exterior working-circuit supplied from the other set of brushes, and means for automatically shifting said brushes to suit the changes in the working resistance.

3. The combination, with a dynamo-electric machine, of two supply-conductors connected in multiple arc from the armature, one including the field-magnets and the other a working resistance or resistances, means for compensating for changes in the distribution of current consequent upon changes in the working resistance, so as to keep the field constant, and regulating devices for adjusting the current supplied to the exterior circuit to suit the changes of resistance on such circuit.

4. The combination, with a dynamo-machine whose field-magnet coils are in a derived circuit, of means for automatically regulating the current flowing around the field-magnet, so as to correct any changes of magnetism produced by changes in the external or working circuit or circuits, and thus keep the magnetism constant, and an external or working circuit provided with independent regulating devices for regulating the current to suit the changes in the external resistance.

5. The combination, with a dynamo-electric machine having its field-magnetism maintained by a current derived from the armature, of means for automatically regulating the magnetizing-current, so as to correct the field-magnetism and keep it constant, despite any tendencies to variation due to variation in distribution of current in the derived circuit supplying the field and the main or working circuit, and an automatic regulator for adjusting the current in the main or working circuit to any change of working resistance.

6. The combination, with a dynamo-electric

machine, of two or more sets of commutator-brushes bearing on the same commutator-cylinder, each set supplying a separate or independent circuit, and independent means for automatically adjusting said brushes.

7. The combination, with the same commutator-cylinder for a dynamo-electric machine, of two or more sets of independently-adjustable commutator-brushes, each set supplying an independent circuit.

8. The combination, with a dynamo-electric machine, of two or more working-circuits, each connected with an independent set of commutator-brushes bearing on the same commutator-cylinder, and means for automatically shifting a set of brushes in accordance with changes in the working resistance with which such set is connected.

9. The combination, with a dynamo-electric machine, of several sets of commutator-brushes bearing on the same commutator-cylinder, and means for automatically adjusting said sets of brushes independently of one another, according to changes in the resistance of their respective circuits.

10. The combination, with the commutator-cylinder, of a set of commutator-brushes mounted on a ring encircling said cylinder, and supported on friction-wheels, as and for the purpose described.

11. The combination, with the ordinary commutator-brush, of auxiliary sets of brushes mounted on independent ring or wheel supports encircling the commutator-cylinder, as and for the purpose described.

12. The combination, with a dynamo-electric machine, of two or more sets of auxiliary commutator-brushes independently adjustable, each set supplying a separate multiple-arc circuit, and a governing electro-magnet for said adjustable brushes placed in a multiple-arc branch, substantially as and for the purpose described.

13. The combination, with a dynamo-electric machine, whose field-magnetism is maintained by a local circuit from the commutator-brushes, of two or more auxiliary sets of commutator-brushes independently adjustable, each set supplying a multiple-arc circuit, and a governing electro-magnet for an auxiliary set of brushes placed in one of the multiple-arc branches.

14. The combination, with a dynamo-electric machine having its field-magnetism maintained by a local closed circuit from the commutator-brushes, of means for automatically adjusting said brushes controlled by the magnetism induced by the current in such local circuit, one or more exterior multiple-arc working-circuits, each connected to one set of a series of auxiliary adjustable commutator-brushes, and means for automatically adjusting said auxiliary sets controlled by electro-magnets in one of the several multiple-arc branches for the respective working-circuits.

15. The combination, with the commutator

for a dynamo-electric machine, of one or more auxiliary commutator-brush supports, E, consisting of rings encircling, but out of contact with, the commutator-cylinder mounted on 5 rollers F F² F³, and encircling the commutator-cylinder.

16. The combination, with the commutator-brush supports E, of the guide and supporting rollers F F² F³, substantially as described.
17. The combination, with the adjusting or regulating mechanism for a dynamo machine, of an operating lever or handle moving over a scale graduated to candle-power of the elec-

tric lamps, whose current is governed by such regulating mechanism.

18. The combination, with the retractile spring for the regulator of a dynamo-machine, of an adjusting device, and a scale over which such device moves, graduated to candle-power.

Signed at New York, in the county of New 20 York and State of New York, this 2d day of May, A. D. 1883.
